UNITED STATES PATENT OFFICE.

WILLIAM VOLKHARDT, OF STAPLETON, NEW YORK.

PORTABLE WARDROBE-RACK.

1,159,813.

Patented Nov. 9, 1915.

Specification of Letters Patent. Application filed October 5, 1914. Serial No. 865,136.

To all whom it may concern:

Be it known that I, WILLIAM VOLKHARDT, a citizen of the United States, residing at Stapleton, in the county of Richmond and 5 State of New York, have invented a new and useful Portable Wardrobe-Rack, of which the following is a specification.

The present invention appertains to clothes racks, and aims to provide a portable 10 wardrobe or garment rack of novel and improved construction.

This invention contemplates the provision of a wardrobe rack of unique construction, whereby it may be applied within the 15 corners of bed rooms, bath rooms, and the like, in a thoroughly effective manner, for supporting clothes, towels, and the like.

It is also the object of the present invention, to provide a wardrobe rack, which may 20 be readily detached from the corner of the room, and folded into a compact relation for enabling the same to be carried conveniently within a trunk, suitcase, or the like.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed can be made within the scope of what is claimed without departing from the spirit of the invention.

35 The invention has been illustrated in its preferred embodiment in the accompanying drawing, wherein:—

Figure 1 is a perspective view of the device as applied to the corner of a room. Fig. 40 2 is an enlarged horizontal section of the device in unfolded condition, parts being broken away. Fig. 3 is a plan view of the device in folded position for the purpose of storage or transportation.

45 In carrying out the present invention, there is provided a pair of bars 1 and 2, which are provided at adjacent ends with hinge butts 3 which are pivoted together, to enable the bars 1 and 2 to be swung at right 50 angles to one another, and also enable the said bars to be swung together, as seen in Fig. 3 when the device is to be folded. Suitable clothes hooks 4 and 5 are pivoted to the adjacent sides of the bars 1 and 2, for supporting articles of wearing apparel, um-

rellas and the like. Spurs or teeth 6 are riveted to or otherwise engaged to the bars 1 and 2 and project from the remote sides thereof, the bar 1 being provided with a tooth or spur 6 adjacent each end, while the 60 bar 2 is provided with a single tooth or spur 6 projecting from a point adjacent its free end. The bar 1 is provided at its free end portion with a longitudinal series of apertures 7, while the free end of the bar 2 is 65 provided with hinged butts 8.

A diagonal rod 9 is provided, for holding the bars 1 and 2 in unfolded or open position, the rod 9 having a hook-shaped bend or curved portion 10 at one end which terminates in an eye or hinged butt 11 pivoted to the hinged butts 8 at the free end of the bar 2, and the rod 9 is provided at its free end with the portion 12 extending on a compound curve, and projecting in the same 75 general direction from the axis of the rod 9, as the portion 10. The portion 12 terminates in a reduced end or nib 13 which is engageable in the apertures 7.

The present rack may be applied in the 80 corners of various rooms, and in applying the device, the bar 1 is first placed against one wall of the room at the desired corner and the prongs or teeth 6 forced into the wall. The bar 2 is then swung against the 85 adjacent wall to cause the tooth or spur 6 thereof to take into the said wall, and finally, the diagonal rod 9 is swung into co-operative relation with the bar 1 and has its terminal 13 engaged into one of the apertures 7. By springing the rod 9, and engaging the end 13 thereof in the innermost 90 aperture 7 possible, the rod 9 will by its tension, yieldably separate the bars 1 and 2, to cause them to tightly grip or bind between 95 the walls of the room, and the rack will thus be held firmly in place to support the clothes or other articles. The terminal portions 10 and 12 of the rod 9 will space the body portion of the rod outwardly from the ends of 100 the bars 1 and 2, in order that a curtain may be supported from the rod 9 to conceal the clothes and to complete the wardrobe. It is thus an easy matter to provide a wardrobe within the corner of a room, by the application of the present rack to the walls of the 105 said corner, as above indicated. The free end 13 of the rod 9 being engageable in the series of apertures 7, may adjust the bars 1 and 2 for various corners, even when the 110

walls are not arranged strictly at right angles to one another, and furthermore, the adjustment aforesaid will enable the bars 1 and 2 to be forced against the walls under 5 tension. The bars 1 and 2 being hinged together may be readily applied to the walls and the rod 9 being hinged to the bar 2, may be readily swung into coöperative relation with the bar 1, and furthermore, the present 10 device may be readily detached from the walls by first disengaging the rod 9 from the bar 1, and then successively disengaging the bars 2 and 1 from the walls. The device may then be folded into a compact condition, 15 as suggested in Fig. 3, by first swinging the bars 1 and 2 together, and then swinging the rod 9 against the bar 1 so that the curved portion 10 accommodates the free end of the bar 1, and whereby the angular free portion 12 of the rod 9 will swing past the hinge of the bars 1 and 2. The device may thus be folded within a small compass, to be conveniently stored or carried within a suitcase, trunk, or the like, and as a result, the 20

rack may be carried by traveling men and 25 the like.

Having thus described the invention, what is claimed is:—

A wardrobe rack embodying a pair of bars hinged together having clothes hooks and 30 wall engaging means, one bar having a series of apertures at its free end, and a rod having a curved portion at one end hinged to the free end of the other bar, and having a curved portion at its free end engageable in 35 the said apertures, the bars and rod being foldable together whereby the first mentioned curved portion of the rod will accommodate the free end of the first mentioned bar, and the other curved portion of the rod 40 may be swung past the hinge of the bars.

In testimony that I claim the foregoing as my own, I have hereto affixed my signature in the presence of two witnesses.

WILLIAM VOLKHARDT.
